Primary Examiner — John M Otte

(57) **CLAIM**

The ornamental design for a display screen with graphical user interface for accessing cluster information, as shown and described.

DESCRIPTION

FIG. 1 is a front view of a first image in a sequence for a display screen with graphical user interface for accessing cluster information, showing our new design; and FIG. 2 is a front view of a second image thereof.

The broken line showing of a display screen is included for the purpose of showing portions of the article that form no part of the claim.

Shaded portions shown in crosshatching illustrate a contrast in appearance.

The appearance of the transitional image sequentially transitions between the images shown in FIGS. 1-2. The process or period in which one image transitions to another image forms no part of the claimed design.
